HERSCHEL E. TOWER, OF CINCINNATI, OHIO, ASSIGNOR TO THE BALDWIN COMPANY,
OF CINCINNATI, OHIO.

MOTOR HANGER FOR MECHANICAL MUSICAL INSTRUMENTS.

Application filed February 4, 1926. Serial No. 85,956.

This invention relates to improvements in motor hangers, particularly adapted for use in pneumatically operated musical instruments for which the power is furnished by 5 an electric motor for the operation of the pneumatic pump that creates the vacuum for the player action.

The object of this invention is to minimize the noises due to electrical and mechanical 10 vibration of the motor before the vibration reaches any part of the piano structure where it would be amplified. A further object is to make a hanger that is simple to construct and durable and that also has a 15 means for taking up the slack of the belt, thereby maintaining a better grip and more power.

A further object of this invention is to have the motor mounted in such a manner 20 as to be self alining with the pulley of the pump, thereby causing minimum wear of the belt.

Fig. 1 is a front view of the lower part 25 of a piano showing the pneumatic pump and the electric motor suspended by the resilient hangers. Fig. 2 is an end view of the electric motor and hanger, showing how the hangers are made in the shape of a loop to give rigidity to overcome the sidewise pull 30 of the belt.

Referring more particularly to the drawings, the electric motor 1 is mounted on two pieces of wood 2 and 3 which are held suspended from the keybed 4 by the hangers 5 and 6, which hangers are fastened to the keybed by the blocks 7 and 8. The blocks 35 2, 3, 7 and 8 have the holes for the hangers made large enough to be bushed with rubber or any other sound deadening material.

40 The pneumatic pump 9 is driven by the electric motor 1 through a belt 10. To keep the belt 10 tight for a good grip on the pulleys so that the motor will transmit sufficient power, a spring 11 is fastened to the 45 hangers 5 and 6 and to a spring support 12 on the bottom board 13 which tends to pull the motor away from the pump 9.

The hangers 5 and 6 are made with a curve so as to have the effect of a spring when the motor is mounted on them. By having these 50 hangers curved and mounted to swing freely, the vibrations are lost before they reach the keybed. The hangers are preferably made in the shape of a yoke, from one piece of material and joined together at the bottom 55 by a collar with set screws. By having these hangers made in one piece there is no tendency for the motor to be pulled sidewise by the belt, as would be the case if they were made of four separate pieces.

The motor 1 is screwed to the blocks 2 and 3 with an insulation of sound deadening material between them. The holes in the blocks 2 and 3 are made of sufficient size to permit the blocks to slide easily on the 60 hangers 5 and 6. By having the blocks 2 and 3 mounted freely on the hangers the motor will work forward or rearward until the pulley of the electric motor 14 is in 65 perfect alinement with the pulley 15 of the pneumatic pump 9. With these pulleys always in alinement there will be no sidewise pull of the belt.

70 When the current is turned on to operate the motor, the motor swings back and forth enough to make up for any defects in the pulleys or belt and any vibrations that start through the frame of the motor are gradually eliminated by the springing of the 75 hangers 5 and 6 so there is no vibration left 80 where the hangers are connected to the blocks 7 and 8.

What I claim as my invention is:

An electric motor with a pulley for driving the pulley on a pneumatic pump, and two 85 loopshaped curved spring hangers for supporting said motor; the radius of curvature of the said hangers being parallel to the plane of rotation of the pulleys on said motor and pneumatic pump.
